(57) CLAIM

The ornamental design for a replaceable shoe heel tip, as shown and described.

DESCRIPTION

FIG. 1 is a front elevational view of a replaceable shoe heel tip;

FIG. 2 is a left side elevational view thereof;

FIG. 3 is a right side elevational view thereof;

FIG. 4 is a rear elevational view thereof;

FIG. 5 is a top plan view thereof;

FIG. 6 is a bottom plan view thereof; and,

FIG. 7 is a top perspective view thereof.

The broken line portions of FIG. 6 are included to show unclaimed subject matter only and form no part of the claimed design.
